UNITED STATES PATENT OFFICE.

WILLIAM L. PIKE, OF GROTON, NEW YORK.

CHOPPING-KNIFE.

SPECIFICATION forming part of Letters Patent No. 528,562, dated November 6, 1894.

Application filed January 24, 1894. Serial No. 497,869. (No model.)

To all whom it may concern:

Be it known that I, WILLIAM L. PIKE, of Groton, in the county of Tompkins, in the State of New York, have invented new and 5 useful Improvements in Chopping-Knives, of which the following, taken in connection with the accompanying drawings, is a full, clear, and exact description.

This invention relates to choppers, adapted 10 for the mincing or cutting of meats, vegetables, or other material.

My object is to improve upon such choppers, whereby I am enabled to produce a shearing, sawing, or longitudinal movement upon the 15 material to be cut by the downward motion of the knife; and to accomplish this and serrate or scallop the cutting edge or edges of the knives so that as the blade passes downward the material to be cut passes longitudinally along 20 the upward edge of the serration, thereby producing the same effect by a downward stroke of the knife that is accomplished by the downward and longitudinal movement of a blade with a plain edge; and to that end 25 my invention consists in the several new and novel features and combination of parts hereinafter described and which are specifically set forth in the claim hereunto annexed. It is constructed as follows, reference being had 30 to the accompanying drawings, in which—

Figure 1, is a side view of the knife, complete. Fig. 2, is an edge view thereof. Fig. 3, is a bottom plan view of the handle at the point where it is secured to the blades. Fig. 35 4, is an edge view thereof. Fig. 5, is a blank blade which may be bent to form two blades of a knife. Fig. 6, is a view of the blank before it is bent. Fig. 7, shows an ordinary chopping knife, provided with my improvements.

—A— is a blade having its cutting edge preferably curved and its edges serrated or scalloped, as shown at —a—, said edges being sharpened clear to the points; and —B— is 45 a handle, of any form desired, having an enlargement —C— at its base perforated centrally and provided with downwardly projecting lugs —c— for the purposes herein-after specified.

50 The knife may be made with a single blade,

as shown in Fig. 7, or, in case I desire to make a knife with multiple blades, may be made as shown in Fig. 2, in which each of the upper ends —d— of the blade may be bent over at substantially a right angle, as shown in 55 Fig. 2, each having a perforation —e— concentric with each other when the blades are put together as shown in Fig. 2, and lateral perforations —f— adapted to receive the lugs —c— upon the base of the handle so that 60 when the bolt or thumb-screw —D— is passed through said blades and the handle, the lugs —c— will be forced into the openings —f— and firmly hold the blades in position and prevent lateral or longitudinal displacement. 65

In case I desire to construct the two blades in one piece they may be stamped out from a piece of sheet metal, as shown in Fig. 5, and then bent U-shaped, having the sides or cutting blades substantially parallel, and the 70 handle secured thereto. The lugs —c— then enter in the perforations —f— and keep the handle from turning upon the blades.

In Fig. 6 I show a blank blade stamped from a sheet of metal before the upper end is bent 75 over, as shown in Fig. 2.

I do not limit myself to a chopping blade with two knives, as it will be evident that other blade or blades may be constructed substantially as shown, and mounted between 80 the blades —A—, either allowing their cutting edge to be in substantially the same plane with the edge of the outer blades or not, as desired.

It will be observed that, as the knives are 85 forced down on to the material to be cut, as soon as the extreme points or edge of the blades strike the material, the lateral edges of each scallop will begin to move laterally upon the material, thereby cutting the mate- 90 rial by a slightly drawing motion, which greatly facilitates the same.

What I claim is—

In a chopping knife the combination of a handle provided at its lower end with a disk 95 having formed therein an opening or passage and having on its under side, on opposite sides of such opening, a pair of downwardly projecting studs, a blade having its upper portion bent to extend substantially at right 100

angles to its body and provided with openings adapted to receive the studs on alignment with the opening in the disk at the lower end of the handle, a headed bolt extending through the aligned openings in the blade and the disk carried by the handle, and a thumb nut secured on the upper end of such bolt and bearing against the upper sur-

face of said disk, substantially as shown and described.

In witness whereof I have hereunto set my hand this 20th day of January, 1894.

W. L. PIKE.

In presence of—

HOWARD P. DENISON,
M. M. BORST.
